UNITED STATES PATENT OFFICE.

CHARLES J. NASH, OF CHICAGO, ILLINOIS, ASSIGNOR TO UNIVERSAL DRAFT GEAR
ATTACHMENT CO., A CORPORATION OF ILLINOIS.

RAILWAY-CAR.

1,209,010.

Specification of Letters Patent. Patented Dec. 19, 1916.

Application filed September 12, 1913. Serial No. 789,445.

To all whom it may concern:

Be it known that I, CHARLES J. NASH, a citizen of the United States, and resident of Chicago, county of Cook, and State of Illinois, have invented certain new and useful Improvements in Railway-Cars, of which the following is a specification, and which are illustrated in the accompanying drawings, forming a part thereof.

- 10 The invention relates to the means for transmitting to the car pulling and buffing stresses, and more particularly to the draft arms and their relation to and connection with the sills and transom of the car.
- 15 The objects of the invention are to provide a draft arm of light weight but great strength, and adapted to communicate the stresses of service not only to the sills but to the transom, together with means for transmitting buffing stresses through the bolster at the end of the car to which they are applied to the bolster at the opposite end of the car.

The invention consists in a structure such as is hereinafter described, and as illustrated in the accompanying drawings, in which—

Figure 1 is a view of the draft arm in perspective, showing its inner face; Fig. 2 is a similar view showing the outer face of the arm; Fig. 3 is an elevation of the draft arm as applied to the sills of a railway car, the inner face of the arm being shown and some of the parts being in section, the outline of some portions of the draft rigging being shown in dotted lines; Fig. 4 is a sectional detail on the line 4—4 of Fig. 2; Fig. 5 is a sectional view on the line 5—5 of Fig. 3; Fig. 6 is a sectional view on the line 6—6 of Fig. 3; Fig. 7 is a detail longitudinal vertical section of the car; and Fig. 8 is a detail plan view of the underframing of the car.

The draft arm is an integral casting, and is shown as extending from the plane of the front face of the buffing plate 10 backwardly over and beyond the bolster 11. The arm is provided with suitable draft shoulders 12, 13, so located as to coöperate with the lower plates of the draft gear which is to be used in connection with it, and is shown as having an aperture at 14 between the draft shoulders for accommodating the transverse rod of a Cardwell gear and at 15 to accommodate a key, as 16, for connecting a coupler, as 17, with a yoke 18.

The arm is adapted to be fitted to the under face of a sill 19, and is provided with an upper horizontal flange 20 which bears against the lower face of the sill and is provided with suitable bolt-holes to accommodate the bolts, as 21, to pass through the sill. The upper face of the arm is also provided with bosses 22, 23, which enter suitable recesses or gains in the under face of the sill and transmit the stresses thereto. The flange 20 extends to the forward end of the arm and is bolted to the buffing plate, as shown at 24, and is offset downwardly to form a shoulder 25 which bears against the rearward face of this plate. A lug 26 extends upwardly from the arm and faces forwardly, and is so disposed as to abut against the rearward face of the end sill 27.

At its forward end the arm is provided with a vertical rib 28 on its inner face, which forms a stop for limiting the lateral movement of the coupler. The rearward end of the body portion of the arm takes the form of a vertical shoulder 29, adapted to bear against the front face of the bolster 11, and an extension 30 of the arm projects upwardly and backwardly over the bolster along the inner face of the sill 19 and is provided with a downwardly extending lug 31 for engaging a casting 32 comprising a body portion 32^a in the form of a plate, located between and extending under the center sills 19 of the car and abutting against the rearward face of the bolster 11, and timbers 33 fitted to the lower faces of the sills and which are preferably of such length as to coöperate with a similar plate at the opposite end of the car, as shown in Fig. 7. The extension 30 of the draft arm is bolted to the casting 32, as shown at 34.

Heavy buffing stresses tend to depress the forward end of the sills and to break them directly over the bolster. The draft arms herein shown and described, with their extensions over the bolster and secured to the casting 32, provide for a cantaliver action for reinforcing the sills against this destructive action, as downward pressure upon the draft arms results in an upward pressure of the member 32 against the bottoms of the sills, which pressure is, of course, resisted by the entire weight of the car. By tying the draft arm extensions together by means of the member 32, the two arms

act as a unit, and any excess of strain placed upon one of them is resisted by both of the sills back of the bolster.

Between the rearward draft shoulder 43 and the shoulder 29 the body portion of the arm occupies two planes, its upper portion 35 being preferably alined with the inner face of the sill 19 and its lower portion 36 being offset outwardly, the two portions being united by a horizontal section 37. By this formation the portion 35 forms a column for supporting the draft shoulder at its inner edge and thus transmitting buffing stresses in a direct line to the bolster, while the lower section 36 transmits the pulling stresses in a direct line, whereby the tendency to fracture under these stresses is reduced to a minimum. Furthermore, the horizontal intermediate section 37 constitutes a substantial reinforcement of the arm, and there is secured a maximum of strength without the use of a great weight of metal.

The arm is further strengthened by an outstanding flange 28 along its lower face, and to which tie plates, such as 39, 40, may be attached. An upstanding flange 41, located between the bosses 22, 23, lies against the inner face of the sill and may have an instanding flange 42 to which an upper tie plate 43 may be secured.

I claim as my invention—

1. In a railway car, a draft arm having a buffing shoulder, a shoulder adapted to abut against a bolster, and a body portion between the shoulders, such portion comprising an upper section in a plane adjacent the inner edge of the buffing shoulder, and a

lower section in a plane adjacent the base of such shoulder and both sections being at least in part within the vertical limits of 40 such shoulder.

2. In a railway car, a draft arm having a buffing shoulder, a shoulder adapted to abut against a bolster, and a body portion between the shoulders, such portion comprising an upper and a lower section, one of said sections being in a plane adjacent the inner edge of the buffing shoulder and the other of said sections in a plane adjacent the base of such shoulder and both sections being at least in part within the vertical limits of 45 such shoulder.

3. In a railway car, a pair of center sills, bolsters, draft arms secured to both ends of 50 the sills and abutting against the outer faces of the bolsters, plates located back of and abutting the inner faces of the bolsters and engaging both sills, and buffing timbers secured to the sills and abutting both of such plates.

4. In a railway car, a pair of center sills, bolsters, draft arms secured to the sills and abutting the outer faces of the bolsters, plates located back of and abutting the bolsters, buffing timbers secured to the sills and 55 abutting both of the plates, each draft arm being provided with an extension arching over the bolster and hooking over the adjacent plate.

CHARLES J. NASH.
